(57) CLAIM

The ornamental design for “bottle insect catcher”, substantially as shown and described.

DESCRIPTION

FIG. 1 is a top front perspective view of the bottle insect catcher showing my new design;
FIG. 2 is a top plan view thereof;
FIG. 3 is a bottom plan view thereof;
FIG. 4 is a right side elevation view thereof;
FIG. 5 is a left side elevation view thereof;
FIG. 6 is a front elevation view thereof;
FIG. 7 is a rear elevation view thereof; and,
FIG. 8 is a cross-sectional view thereof taken along line 8—8 FIG. 4.

The broken line showing of environment in the drawings is for illustrative purposes only and forms no part of the claimed design.
